APPARATUS FOR PRESHAPING SHOE
UPPER MATERIALBernard S. Steiner, Kirksville, Mo., assignor to
The Peerless Machinery Company, Boston,
Mass., a corporation of Massachusetts

Application November 2, 1934, Serial No. 751,173

13 Claims. (Cl. 12—51)

This invention pertains to shoe manufacture and relates more particularly to an improved method of and apparatus for use in preshaping a portion of the shoe upper, for example, the heel portion of the quarter lining, preparatory to lasting, whereby to facilitate the pulling-over and lasting operations and to produce a shoe of high quality.

While the method and apparatus herein described are of broader utility and might, for example, be employed in preshaping any of the constituent parts of a shoe upper, inclusive of the heel, toe and other parts, and doubtless for other purposes, I have herein chosen to disclose it with particular reference to its applicability to the preshaping of the quarter lining of the shoe.

According to usual practice, the rear or heel end of a shoe last is of convex curvature, bulging rearwardly to a substantial extent between its lower (or heel seat) edge and its upper edge. Since the quarter lining is cut from substantially flat or sheet-like material, for instance cloth or leather, it has heretofore been necessary, in pulling the upper over the last or in the subsequent heel-seat lasting operation, to apply a severe stretching stress to the rear end of the upper, including the lining, so as to cause it to conform to the bulge of the last.

Ordinarily the quarters of the upper proper, (that is to say, the outer element of the upper with its attached doubler, if any) are united by a seam which is located substantially at the center line of the rear or heel end of the shoe, and by cutting the meeting edges of these two quarters to a suitable curvature, it is possible, to some extent at least, to preshape the heel end of the upper proper so as more or less to conform to the bulge of the last. Thus in pulling over and lasting the upper proper, it is not necessary to impose a damaging strain upon the material. However, it is customary in making shoes of the better grades, at least, and in order to avoid an undue ridge or rib at the heel end of the shoe, to make the quarter lining of a single piece or, if of more than one piece, to arrange the seam or seams uniting the several parts so that such seam or seams is or are disposed on one or both sides of the center line of the heel end of the upper. In this way registry of the lining seam with the seam in the upper proper is avoided.

While in theory this method of procedure should make a shoe more comfortable to the wearer than though the seams were in registry

with one another, it is obvious that it precludes the preshaping of the rear end of the lining in cutting the parts so that the rear or heel end of the lining is normally devoid of any bulge or outward curvature. In consequence, so great a pulling stress is required in pulling over the upper, or, in heel-seat lasting, in order effectively to conform the lining to the last, that many shoes are damaged in this operation, and at best the lining never conforms as it should to the last, and tends to sag and wrinkle when in use, to the annoyance and discomfort of the wearer.

In accordance with the present invention I preshape the rear end of the lining, at some point in the operation prior to the pulling over of the upper,—preferably before the lining is united to the other parts of the upper. In thus preshaping the heel end of the lining I cause the material at this point to be so stretched as to form a large dimple or concavity at its inner face which approximates the curvature of the rear end of the last. Thus in pulling over, far less strain is necessary to conform the lining to the last than is required in the ordinary process. While this step of preforming the lining is particularly useful in lasting shoes wherein the quarter lining is devoid of a seam or has the seam or seams laterally offset from the center line of the heel, I contemplate its usefulness in the manufacture of cheaper grades of shoes having the quarter linings seamed at the center of the heel, since it helps properly to shape such lining, even if the lining has been cut to provide some degree of curvature at this point.

For carrying my process into effect I provide mechanism of a simple and efficient type, preferably comprising what in effect is a hollow die into which the heel end of the lining is forced and stretched by the application of an appropriately shaped plunger member. Preferably the die or the plunger or both is or are heated to a predetermined temperature and the plunger is so actuated by appropriate mechanism that, after it has forced the material of the lining into the die cavity, it dwells or remains stationary for a predetermined period so that the lining material acquires a permanent set in its stretched position.

After the completion of this stretching operation, the lining bulges rearwardly at the heel end, providing a large dimple or cavity in its inner surface adapted to conform more or less closely to the rear surface of the last. When the upper, having the preformed lining, is assembled with the insole on the last and pulled over, little diffi-

culty is experienced in pulling and lasting it snugly about the rear end of the last.

In following usual modes of procedure, an air pocket is sometimes formed behind the lining at the heel of the shoe, due to the failure of the lining to stretch so as to conform to the curvature of the last. When such an air pocket is formed the lining is left loose and does not fit nor wear well. The present invention prevents formation of such air pockets behind the lining, and in the completed shoe the lining shows substantially no tendency to sag or develop wrinkles.

In accordance with the present invention I preferably provide a hollow die of a type which readily accommodates itself to differences or inequalities in the thickness of the lining material, and to cooperate with this die I employ a plunger so shaped as to avoid cutting or abrading the surface of the lining material when the latter is forced into the cavity of the hollow die. This plunger is of such contour as, in cooperation with the walls of the die, to stretch the lining material and impart the desired fullness at the heel portion of the latter. To enhance the stretching and shaping of the lining material I contemplate the provision of presser feet or equivalent clamping devices operative to hold the material at each side of the hollow die as the plunger enters the latter, thereby to localize the stretching and bulging of the material and thus prevent unduly deforming other parts of the lining.

Preferably the machine is provided with a one-revolution clutch or equivalent device to ensure a proper interval of time between successive advance movements of the plunger, thereby to permit ready insertion and withdrawal of the work. The machine also comprises mechanism, as for example a cam, for actuating the plunger so that after it has been advanced into the die it remains stationary for a predetermined period, for instance two seconds, and is then quickly retracted to leave the die free for removal of the work and insertion of a new piece.

In the accompanying drawings in which I have illustrated one desirable embodiment of the invention by way of example,—

Fig. 1 is a front elevation of the machine;

Fig. 2 is a rear elevation of the machine;

Fig. 3 is a side elevation with certain parts in vertical section, substantially on the line 3—3 of Fig. 1;

Fig. 4 is a fragmentary vertical section, to larger scale, substantially on the line 4—4 of Fig. 3;

Fig. 5 is a fragmentary vertical section looking from the right-hand side of the machine and with the flywheel removed, showing details of the clutch mechanism;

Fig. 6 is a plan view, to small scale, showing a one-piece quarter lining before it has been embossed or indented;

Fig. 7 is a fragmentary side view of the quarter lining folded and showing the heel portion with the bulge or dimple therein as produced in accordance with the present method; and

Fig. 8 is a horizontal section, to small scale, illustrating a modified form of plunger and die.

Referring to the drawings, the machine is illustrated as comprising a base 1 (Fig. 2) adapted to be bolted to a suitable table, bench or the like, such base being provided with a pair of substantially parallel upright members 2 and 3. These upright members are provided with bosses having aligned bearing openings for a main drive shaft 4 which projects at the right-hand side of the machine and is there furnished with a pulley

or fly-wheel 5. This pulley is normally loose on the shaft but may be connected thereto for driving the latter by means of a one-revolution clutch 6 of any usual type. Clutches of this general type are commonly used in punch presses and similar mechanisms where it is desired to have the machine go through a single cycle of operations and then stop. Since such clutches are well known and since the clutch forms no essential part of the present invention, it is unnecessary to describe it in detail. A clutch of a type which might be employed for the purpose is shown in the patent to Allen No. 743,213, dated November 3, 1903.

In the present instance the clutch is controlled by means of a treadle-actuated rod 7 (Fig. 5) which passes up through an opening in the base member 1 and through an aligned guide opening in a bracket 8 projecting from the right-hand frame member. The upper end of this rod cooperates with a pin 9 forming the release element of the clutch device so that when the rod is moved downwardly the clutch parts are connected, thereby to transmit motion from the pulley to the drive shaft 4. A rod 10, also guided in the opening in the base member 1 and near its upper end in a bracket 12 projecting from the right-hand frame member 2, is fixedly united to the rod 7 by means of a bracket 11 beneath which a coil spring 11a encircles the rod 7 and normally acts to lift the rod 7 into position to release the clutch drive elements. The upper end of the rod 10 cooperates with a positive stop cam 13 having a stop shoulder 14 and fixed to the shaft 15. When the upper end of the rod 10 engages the shoulder 14 the shaft 15 is positively stopped in predetermined position.

The shaft 15 (Fig. 2) is journaled in bearing bosses carried by the frame members 2 and 3 and carries a gear 16 which meshes with a pinion 17 fixed to the shaft 4. The gear 16 is of considerably larger diameter than the pinion 17, for example, having a four-to-one ratio to the latter so that the shaft 15 is driven at a relatively low speed.

A shaft 18, at the upper forward part of the machine, is journaled to turn in bearing bosses 19 (Fig. 1) projecting inwardly from the frame members 2 and 3. This shaft 18 supports a lever (Fig. 3) comprising a rearwardly directed arm 20 and a forwardly directed arm 21. The arm 20 is bifurcated at its rear part to provide spaced lugs 22 which support a shaft 23 on which is mounted a cam follower roll 24 which engages the periphery of a cam 25 fixed to the shaft 15. This cam is provided with a concentric dwell portion 26, preferably of substantially more than 180° extent, with a plunger actuating face 27 and a release surface 27a. A spring 20a secured to the lever arm 20 tends to hold the cam follower roll 24 constantly in engagement with the periphery of the cam 25. The forward arm of the lever 21 (Fig. 3) is provided with a pin 28 to which a pair of links 29 is secured. The lower ends of these links are connected by a pivot pin 30 to the upper end of a rod or stem member 31 mounted to slide vertically in a boss 32 carried by a bracket 33 projecting from a web member 33a which unites the uprights 2 and 3. The stem 31 supports the plunger assemblage 34 which comprises a head 35 fixedly secured to the lower end of the stem and to which is removably secured a support 36 which may be attached by means of bolts 37. This support may readily be removed when desired to permit exchange for another carrying

a plunger of a different size or contour. The plunger 38 projects downwardly from the lower surface of the plate 36, and in the arrangement shown in Figs. 3 and 4 this plunger takes the form of a plate-like member having its right and left surfaces substantially flat and parallel, while it is of more or less V-shape in contour, viewed from the side (Fig. 3). The edges of this plunger member 38 are smoothly rounded as shown at 39 (Fig. 4) so as not to cut or abrade the work.

Beneath the bracket 33 is a second bracket 40 which supports the die assemblage. This bracket has a boss 41 provided with a vertical bore which receives the sliding stem or plunger 42 supporting the die head 43. This plunger 42 is resiliently supported by a spring 44 which rests upon a tubular screw-threaded sleeve 45 having screw-threaded engagement with the lower end of the bore in the boss 41. A rod 46, passing freely up through the sleeve 45, has threaded connection to the stem 42 and at its lower end is provided with an adjustable stop nut 47. By turning this nut the tension of the spring 44 may be varied as desired. A stud 48 projecting down from the die head 43 into an opening in the bracket 40 prevents the die head from turning horizontally. The die head preferably is provided with a cavity which receives a heating unit 49 of any desired type, but here shown as electrical and supplied with current through a flexible conductor 50.

The upper part of the die head 43 is shaped to provide the central member 51 (Fig. 4) of the die assemblage. This member 51 preferably is of substantially the same lateral width or thickness as the plunger member 38 and is provided in its upper surface with a depression or recess, of more or less V-shaped contour, viewed from the side (Fig. 3). This recess extends laterally across the entire thickness of the part 51 so that it is open at its opposite sides. The die assemblage also comprises plate-like members 53 and 54 (Fig. 4) which constitute the side walls for this recess. The members 53 and 54 are arranged to slide laterally each on a pair of pins 55, 56, respectively, secured to the central die member 51 forwardly and rearwardly, respectively, of the cavity 52. These pins 55 and 56 are furnished with adjustable nuts 58 and 59 at their outer ends and are surrounded by coil springs 60 and 61, respectively, which resiliently urge the plates 53 and 54 toward the central member 51 of the die assemblage. The upper edges of the plates 53 and 54, and the upper edge of the central member 51 of the die (forwardly and rearwardly of the cavity 52) are disposed substantially in the same plane to provide a work-supporting surface. This work-supporting surface is preferably extended laterally by means of fixed brackets 62 and 63 secured to the frame of the machine.

In order to hold the work 64 properly in contact with the work-supporting surface during the embossing operation, I may, if desired, provide the plunger head 35 with lateral offsets 65 and 66 (Fig. 4) having openings for rods 67 and 68 provided at their lower ends respectively with resilient presser feet 69 and 70. These feet may be of felt, rubber or the like and are resiliently urged downwardly by means of springs 71 and 72 interposed between the feet 69 and 70 respectively, and the under surfaces of the parts 65 and 66. Thus the presser feet move downwardly onto the work in advance of the plunger member 38, but yield as the plunger completes its downward movement. While these presser feet are desirable to assist the operator in holding the work 64

in position, they may be dispensed with and the operator may hold the work in taut position by means of his fingers.

The blank 64 (Fig. 6) is laid upon the work-supporting surface with its rear edge in contact with a gauge member 75 (Fig. 3) adjustably secured to the upper surface of the central die member 51. The operator then depresses the treadle thereby clutching the drive shaft to the pulley and causing the cam 25 to make a single rotation before the machine automatically comes to rest. As the cam 25 rotates, the roll 24 rides up the active surface 27 of the cam and in so doing the plunger assembly, including the presser feet and plunger 38, are forced downwardly onto the work spanning the die cavity 52. The presser feet first engage the work and hold it taut and the plunger forces the mid portion of the material down into the die cavity so as to form a depression in the material more or less of the contour indicated in broken lines at 73 in Fig. 6. As the plunger member 38 descends into the cavity 52, the central part of the work is forced down between the side plates 53 and 54, and the latter, being yieldable, exert a substantially uniform pressure on the material regardless of slight variations in thickness. Moreover, since these members are yieldable it is unnecessary to have the plunger and die so accurately aligned as would otherwise be essential to obtain desirable results.

When the plunger member 38 has entered the die cavity to its full extent, the roll 24 rides on the dwell 26 of the cam 25 during a very considerable portion of the cycle of operation of the machine. By driving the pulley 5 at proper speed, the plunger may readily be caused to dwell two seconds while in operative position, and in this interval the material which has been stretched is subjected to the heat of the die as well as to pressure, both downwardly and laterally. The material is thus caused to take a permanent set so as to bulge rearwardly, as shown at 73^a (Fig. 7), and form a dimple or cavity 73^b in its inner surface. By making the die cavity and plunger of proper shape this dimple or cavity in the work may be made of such contour as substantially to fit the bulge at the rear end of the shoe last when the upper is assembled on the latter and thus excessive strains in lasting are avoided. As the cam 25 continues to rotate, the cam roll 24 reaches the release surface 27^a, which is of relatively short angular extent so that the plunger is quickly retracted by the action of spring 20^a.

In Fig. 8 I have illustrated a plunger member 38^a of a modified horizontal cross-sectional contour and have shown the die members 51^a, 53^a and 54^a correspondingly shaped. It is obvious that plungers and correspondingly shaped dies of any suitable contour may be employed in accordance with the particular conformation of the dimple or depression which it is desired to make in the work.

While I have herein described one desirable embodiment of the invention by way of example, I wish it to be understood that the invention is not necessarily limited to the precise arrangement herein shown but that any generally similar construction, employing equivalent elements may be employed without departing from the spirit of the invention as expressed in the appended claims.

I claim:

1. A machine for preshaping a shoe lining 75

part, said machine comprising a die having downwardly yieldable bottom and laterally yieldable walls defining a cavity between them, a plunger operative to force the lining material into the cavity between said lateral walls thereby to bulge the lining material, means operative to heat the yieldable bottom of the die, and plunger actuating means operative to cause the plunger to dwell while in cooperative relation to the die until the bulged lining material has acquired a permanent set.

2. A machine for preshaping sheet-like material, said machine comprising a die having spaced relatively movable walls defining a cavity between them, resilient means yieldably urging said walls toward each other, said walls having surfaces collectively forming a work support, a plunger for pressing sheet material resting upon the work support into the die cavity, the plunger being of a width substantially equal to the normal width of the cavity, presser feet operative to hold the sheet material in contact with the work support, and means for moving the plunger into the cavity thereby to force that portion of the sheet material which overlies the cavity into the latter and thereby form a bulge in the material.

3. A machine for preshaping sheet material, said machine comprising a die including a central member having substantially parallel side faces and having a recess in its upper edge, a pair of relatively movable members constituting opposite side walls for the recess, thereby to define a die cavity, yielding means urging said wall members toward the parallel side faces of the central member, a plunger movable into and out of the recess, said plunger being of a width approximating the normal width of the die cavity, and means for moving the plunger into and out of the cavity.

4. A machine for preshaping sheet material comprising a die including a central member having a recess therein, plates disposed respectively at opposite sides of the central member and constituting spaced side walls for the recess, thereby defining a die cavity, the upper surfaces of the plates and of the central member, respectively, being disposed in substantially the same plane and constituting a work-supporting surface, springs urging the respective plates toward the central die member, a plunger movable into and out of the cavity, the advancing end of the plunger having rounded edges, and plunger actuating means operative to move the plunger into the die cavity and to cause it to dwell there a predetermined period before its withdrawal.

5. A machine for preshaping a part of a shoe upper, said machine comprising a die including a central member having a recess in its edge, relatively movable plates constituting spaced walls for said recess, thereby to define a die cavity, independent spring means urging the respective plates toward the central member, a plunger movable into and out of the cavity, the width of the plunger being substantially equal to the minimum distance between said plates, the advancing end of the plunger having blunt edges, and plunger actuating mechanism including a rotary cam having a dwell portion of more than 180° angular extent operative to hold the plunger substantially stationary within the die cavity for a predetermined period, and drive means for said cam including a one-revolution clutch.

6. A machine for preshaping the heel end of

the quarter lining of a shoe, said machine comprising a die having a central member provided with substantially parallel sides and with a recess in its edge, a pair of side plates normally disposed in contact with the parallel sides, respectively, of said central member, springs normally urging the respective side plates toward the central member, said side plates forming relatively yieldable side walls for the recess, a plunger movable into and out of the recess, the plunger being of such a shape and contour as to fit snugly within the recess when the latter is of normal width, means for moving the plunger into and out of the recess, and resilient means supporting the die to permit the latter to yield as the plunger advances into the recess.

7. A machine for preshaping the heel end of the quarter lining of a shoe, said machine comprising a die having a central member provided with substantially parallel sides and with a recess in its edge, a pair of side plates normally disposed in contact with the parallel sides, respectively, of said central member, springs normally urging the respective side plates toward the central member, said side plates forming relatively yieldable side walls for the recess, a plunger movable into and out of the recess, the plunger being of such a shape and contour as to fit snugly within the recess when the latter is of normal width, means for moving the plunger into and out of the recess, yielding means supporting the die in opposition to the pressure exerted by the advancing plunger as the latter enters the recess, and means operative to vary the yielding resistance of the die.

8. A machine for preshaping the heel end of the quarter lining of a shoe, said machine comprising a die having a central member provided with a substantially V-shaped recess, a pair of side members disposed respectively at opposite sides of the central member, said side members having surfaces constituting side walls for the recess, a substantially V-shaped plunger of a contour substantially similar to that of the recess and of a width substantially equal to the normal width of the recess, and actuating means operative to move the plunger into and out of the recess, said actuating means comprising a rotary cam having an active portion operative to move the plunger into the recess, a dwell portion operative to hold the plunger in the recess for a predetermined time, a release portion following the dwell portion, and spring means operative to retract the plunger from the recess when released by the cam.

9. A machine for preshaping the heel end of the quarter lining of a shoe, said machine comprising a die having a central member provided with a substantially V-shaped recess, a pair of side members disposed respectively at opposite sides of the central member, said side members having surfaces constituting side walls for the recess, a plunger of a contour substantially similar to that of the recess and of a width substantially equal to the normal width of the recess, an adjustably yielding support for the die, and plunger actuating means operative to advance the plunger into the recess, to cause the plunger to dwell within the recess, and to retract the plunger from the recess.

10. A machine for preshaping the heel end of the quarter lining of a shoe, said machine comprising a die having a central member provided with a substantially V-shaped recess, a pair of relatively movable side members disposed respec-

75 70 75

tively at opposite sides of the central member, said side members having surfaces constituting side walls for the recess, resilient means urging said side members toward each other, a plunger 5 of a contour substantially similar to that of the recess and of a width substantially equal to the normal width of the recess, an actuating lever, means connecting the plunger to the lever, positive means operative to rock the lever in one direction, and yielding means operative to rock the lever in the other direction.

11. A machine for preshaping the heel end of the quarter lining of a shoe upper, said machine comprising a die having a central member provided with a recess and a pair of side members disposed respectively at opposite sides of said central member, said side members having surfaces constituting side walls for the recess, at least one of said side members being resiliently 15 yieldable away from the central member, the recessed surface of the central member being disposed in substantially the same plane with surfaces of the side members thereby to constitute a work support, a plunger movable into and out of the recess, and work holding means operative to press the work forcibly against the work support as the plunger is advanced into the recess.

12. A machine for shaping sheet material, said

machine having a die including a member provided with a recess, the top and one side at least of said recess being open, a closure member for the open side of the recess, resilient means normally urging the closure member toward the recessed member, retaining means operative to hold the material to be shaped in taut condition spanning the recess, and a plunger operative to force the material into the recess, thereby to stretch the material and to produce a permanent 10 bulge therein.

13. A machine for shaping sheet material, said machine having a die comprising a member provided with a recessed surface, the recess in said surface being open at opposite sides, closure 15 members for the opposite sides of the recess, said closure members and the recessed member having surfaces collectively constituting a work rest for supporting the material so as to span the recess, retaining means engageable with the sheet 20 material at opposite sides of the recess and operative to hold the material firmly against the work rest, and a plunger operative to force the material which spans the recess into the recess, thereby to form a permanent bulge in the material.

BERNARD S. STEINER.
